Atty.

UNITED STATES PATENT OFFICE.

JOHN P. STEVENS, OF NEWBURYPORT, MASSACHUSETTS.

BOOT OR SHOE.

Application filed May 21, 1923. Serial No. 640,374.

To all whom it may concern:

Be it known that I, JOHN P. STEVENS, a citizen of the United States, residing in Newburyport, in the county of Essex and State of Massachusetts, have invented an Improvement in Boots or Shoes, of which the following description, in connection with the accompanying drawings, is a specification, like characters on the drawings representing like parts.

This invention relates to a boot or shoe and has for one of its objects to provide a novel and improved construction of a boot or shoe adapted to afford maximum comfort to the wearer and a correct support for the arch of the foot.

A further object of the invention is to provide a boot or shoe of a strong and durable construction having a sole and shank portion of maximum flexibility.

To these ends the boot or shoe is provided with an arch supporting device which comprises a member for engaging and supporting the arch of the foot, and a rocking member upon which said arch engaging member is mounted. The rocking member is adapted to be positioned within the boot or shoe at the heel and shank portion thereof, and is adapted to support the heel portion of the foot as well as the arch in a manner such that a person wearing the shoe, as he walks along imparts a rocking movement to the rocking member. In this manner the arch supporting member is caused to continuously engage the arch of the foot and to support it in the different positions assumed by the foot corresponding to the different steps or stages in the walking operation without causing undue pressure to be exerted upon the arch. The rocking member may and preferably will comprise a lever pivoted upon a supporting base or plate, and the latter may be preferably secured to the heel portion of the shoe, and the inner sole of the shoe may be cut away to reduce to a minimum the space occupied by the arch supporting device. In order to provide the boot or shoe with a flexible shank portion and yet omit the usual metal stiffening member for the shank, an external reinforcing member is provided for the portion of the shank at the breast of the shoe heel. In the preferred embodiment of the invention this reinforcing member is riveted or otherwise secured to the supporting base

or plate of the improved arch supporting device within the shoe.

These and other features of the invention will be hereinafter described and particularly pointed out in the claims at the end of 60 the specification.

In the drawing illustrating the preferred embodiment of the invention, Fig. 1 represents a side elevation of a shoe partially in section;

Fig. 2, a sectional plan of the heel portion of the shoe shown in Fig. 1 with the rocking member of the arch supporting device removed;

Fig. 3, an inverted plan of the rocking member; and

Fig. 4, a sectional view illustrating the position assumed by the rocking member of the arch supporting device when the shoe heel is raised from the ground when the 75 weight of the person rests upon the ball of the foot.

Referring to the drawings, 10 represents a shoe provided with the improved arch supporting device 12. As herein shown, the 80 arch supporting device 12 comprises a rocking member 13 in the form of a lever provided with a rear portion 15 for supporting the heel of the foot, and with a front member 16 for engaging and supporting the 85 arch of the foot. Both members 15, 16 are preferably provided with cushions 17, 18. The rocking member 13 is arranged to be rocked by the movements of the foot as the person walks along about a pivotal point 90 between the portions 15 and 16, and as herein shown, the rocking member is provided with pintles 19 which are received within U-shaped bearing members 180 95 upstanding from a base plate or supporting member 20. The base plate or supporting member 20 may and preferably will be secured to the heel of the shoe, preferably by screws 22, and in order that the arch supporting device may occupy a minimum space 100 within the shoe, the inner sole at the heel portion of the shoe is cut away and arranged to terminate at a point beyond the forward end of the supporting member or base 20. The arch engaging member 16 may and 105 preferably will comprise a plate curved to conform to the arch and provided with a depending lug 24 by which it is pivotally secured to the forked forward end 25 of the rocking member 13 by a pin 26, as shown.

In order to enable the shank portion of the shoe to be made flexible, the usual metal stiffener is omitted and an external reinforcing member 30, herein shown as a metal angle plate, is arranged to reinforce the shank 31 at the breast of the shoe heel. The reinforcing plate 30 may and preferably will be secured by rivets 32 or otherwise, to the base or supporting member 29 of the arch supporting device, and also by screws 33 to the breast of the shoe heel.

In the operation of the arch supporting device, when a step is taken, the heel of the shoe strikes the ground first, and the weight 15 of the person exerted upon the heel operates to depress the rear or heel portion of the rocking member 13 into the position illustrated in Fig. 4. In such position, it will be observed that the arch engaging member 16 supports the arch of the foot. As the person continues to complete the step, the weight is gradually shifted on to the ball of the foot, and as it is thus shifted, the arch engaging member 16 is itself rocked 25 relatively to the rocking member 13 and into substantially the position shown in Fig. 4, thereby relieving the arch from abnormal pressure as the weight is shifted to the ball of the foot. The arch engaging member 16 is, therefore, at all times maintained in engagement with the arch of the foot and operates to support it. Notwithstanding that the arch engaging and supporting member 16 is maintained at all 30 times firmly in engagement with the arch to support the same, it is nevertheless arranged to move with movements of the foot as the person walks, and therefore undue or harsh pressure upon the arch is avoided. In this 35 manner maximum comfort is afforded the wearer of the shoe and at the same time the arch is positively and correctly supported at all times. The action of the present arch supporting device may be compared to the 40 action obtained when one walks barefoot in sand. In such a case the sand fills the space under the arch of the foot and being yielding acts very similarly to the arch engaging member 16 of the present arch supporting device.

The elimination of the usual metal shank stiffening member from the shank enables a sole and shank of maximum flexibility to be obtained. This feature of construction 45 adds to the comfort of the shoe and prevents the arch engaging member from bearing harshly against the arch of the foot, and danger of the shank being broken down or ruptured at the portion adjacent the heel is

avoided by the reinforcing breast plate, 60 which latter can have its upper flange 40 made of any desired width to adapt it to heels of various sizes and yet provide the reinforcement for the shank.

Having thus described the invention, what 65 is claimed is:

1. A boot or shoe provided with an arch supporting device within the heel and shank portion thereof, comprising a supporting base secured to the heel portion of the shoe, 70 a rocking member pivoted thereon, an arch engaging and supporting member movably mounted upon the forward portion of said rocking member, and a heel supporting member mounted upon the rear of the rock- 75 ing member, the pivotal point of the rocking member being located intermediate the arch and heel supporting members.

2. A boot or shoe provided with an arch supporting device within the heel and shank portion thereof, comprising a supporting base secured to the shoe heel, a rocking member pivoted thereon, an arch engaging and supporting member pivotally mounted upon the rocking member in front of the pivot of 85 the latter, and a member mounted upon the rocking member in the rear of said pivot for supporting the heel of the foot.

3. An arch-supporting device for use within a shoe comprising a pivoted heel-supporting member, and an arch-supporting member pivoted to said heel-supporting member to rock thereon while engaged with the arch of the foot.

4. An arch supporting device for use 95 within a shoe comprising a pivoted heel supporting member and an arch supporting member carried by the pivoted heel supporting member to rock about the pivot therefor and movably mounted upon the heel 100 supporting member to be capable of an independent movement for the purpose specified.

5. An arch supporting device for use 105 within a shoe comprising a supporting base, a rocking member detachably pivoted thereon provided with one portion for engaging and supporting the arch, and a second portion for supporting the heel of the foot said 110 portions being capable of movement independently of each other whereby a rocking movement is imparted to said rocking member as the person walks to cause said first portion to yieldingly engage and support the arch at all times.

In testimony whereof, I have signed my name to this specification.

JOHN P. STEVENS.
